UNITED STATES PATENT OFFICE.

THOMAS W. COX, OF SPRINGFIELD, OHIO, ASSIGNOR OF ONE-HALF TO JACOB LIGHT KOHL,
OF SPRINGFIELD, OHIO.

RAILWAY-SWITCH.

No. 928,632.

Specification of Letters Patent. Patented July 20, 1909.

Application filed February 4, 1909. Serial No. 476,125.

To all whom it may concern:

Be it known that I, THOMAS W. COX, a citizen of the United States, residing at Springfield, in the county of Clark and State of Ohio, have invented certain new and useful Improvements in Railway-Switches, of which the following is a specification, reference being had therein to the accompanying drawings.

10 This invention relates to railway switches, and more particularly to combination switches and crossings.

The object of the invention is to provide 15 operating mechanism for a switch of this character which will prevent the switch points from binding when the switch is thrown from one position to another and will render the operation of the switch free and easy; and further, to provide such a mechanism 20 which will be of a simple construction and not liable to be broken or to become disarranged.

With these objects in view my invention 25 consists in certain novel features of construction and in certain combinations and arrangements of parts hereinafter to be described, and then more particularly pointed out in the claims.

The accompanying drawing is a top plan 30 view of a switch operating mechanism embodying my invention.

In this drawing I have illustrated one embodiment of my invention and have shown the same as comprising the outer curved 35 rails or stock rails 1 and 2 arranged on opposite sides of the switch and curved in opposite directions. Arranged immediately within each of the stock rails 1 and 2 are the bent connecting rails 3 and 4, these rails being 40 curved in the same direction as are the stock rails 1 and 2, and being arranged a short distance therefrom and provided at their ends with switch points 5 and 5^a and 6 and 6^a, respectively. These switch points 45 have their outer ends beveled, as shown, to fit snugly against the side of the adjacent portion of the stock rails 1 and 2 and connect the same with the connecting rail 3. Straight connecting rails or track rails 7, 8, 9 and 10 50 lie within and adjacent to the bent connecting rails 3 and 4 and are provided at their inner ends with switch points 11, 12, 13 and 14, respectively, which points have their inner ends tapered to fit snugly against the 55 sides of the adjacent connecting rails 3 and 4.

Lying within the straight rails 9 are curved connecting rails 15 and 16, which rails are curved in a direction opposite the curvature of the adjacent stock rail and in the same direction as the stock rail farthest removed 60 therefrom is curved. The curved connecting rails 15 and 16 are provided at their outer ends with switch points 17, 18, 19 and 20 having their outer ends beveled to fit snugly against the adjacent sides of the straight 65 rails 7, 8, 9 and 10, respectively.

The inner ends of the switch points 11, 12, 13 and 14 are operatively connected to connecting bars 21 and 22. These bars connect the switch points in pairs, the bar 21 connecting the points 11 and 13 and the bar 22 connecting the points 12 and 14. Suitable means are provided for simultaneously actuating these bars in opposite directions so that, when the switch points 11 and 14 are in 70 engagement with the respective connecting rails 3 and 4, the switch points 12 and 13 will be out of engagement therewith. This means preferably comprises a T-shaped lever 23 having its cross bar 24 connected to the outer ends of the bars 21 and 22 which extend 75 beyond the stock rail 1. The outer end of the T-shaped lever is connected, by means of a link 25, with a lever 26, the point of connection being removed from the pivotal center of the lever, whereby the movement of the lever about its pivotal center will rock the T-shaped lever about its pivotal center and move the bars 22 in opposite directions. The remaining switch points are shown in the 80 drawing as in their central or neutral position and suitable means are provided for actuating these points in such a direction as to close the switch to complete the track in either direction. With the central switch points 11, 12, 13 and 14 in the position shown in the drawing, by moving the switch point 5 into engagement with the adjacent stock rail 1, moving the switch point 20 out of engagement with the connecting rail 10, 85 moving the switch point 17 out of engagement with the connecting rail 7 and also moving the switch point 6 into engagement with the adjacent stock rail 2, a continuous track will be formed through the switch comprising the stock rail 2, switch point 6, connecting point 4, switch point 14 and straight connecting rail 10 on the one side and straight connecting rail 7, switch point 11, bent connecting rail 3, switch point 5 and stock rail 90 110

1 on the opposite side. By shifting the various switch points from one position to another different combinations may be provided to carry a train on one track either 5 straight across the other track or to switch it onto the other track, regardless of the track on which the train may have been in the first place or in which direction it is traveling.

10 In operating switches of this sort great difficulty is experienced from the binding of the switch points due to the unequal throw of the operating mechanism. This binding renders the switch very difficult to operate, 15 and, in order to overcome the same, I have provided the mechanism herein shown and described. This mechanism preferably consists of connecting bars 27 and 28 connecting the switch points 5 and 20, and 6^a and 20, respectively, at one end of the switch and the connecting rods 29 and 30 connecting the switch points 5^a and 19, and 6 and 17, respectively, at the opposite end of the switch. The connecting bars at each end of the switch 25 are preferably arranged close together so that the movement necessary to be imparted to the same to throw the switch points will be substantially the same. The two connecting bars at each end of the switch are 30 connected to opposite ends of the T-shaped lever 31 pivotally mounted upon a supporting base 32, as shown at 33 and this connection may be made in any suitable manner. In the present instance the T-shaped lever 35 35 is removed but a short distance from the switch, and, owing to the close relation of the connecting bars I have found it desirable to provide each bar with a lug 34, to which is secured one end of a rod 35, which rods serve 40 to connect the bars 27 and 28, and 29 and 30 to the opposite ends of their respective T-shaped levers 31. The length of the rods 35 or the other connection between the connecting bars and the T-shaped lever is such that, 45 when the switch points are in their central position, the cross bar 36 of the T-shaped lever will extend in a line substantially parallel with the adjacent portion of the stock rail 1.

50 A suitable actuating bar extends between the levers 31 and serves to actuate the same simultaneously. In the present instance this connecting bar is shown as comprising a series of sections, one of which sections, here 55 shown at 37, is slidably mounted in guideways 38 secured to a base 46 and is pivotally connected at each end to one of the T-shaped levers 31 by links 39 and 40, respectively. Thus, the central portion of the actuating 60 bar is arranged out of alignment with the ends thereof and a substantial curve is imparted to the actuating bar, so that the same extends in a line substantially parallel with the line of the stock rail 1. The construction 65 of the bar is such as to permit of this

curvature, and, at the same time, to permit of the free longitudinal movement of the bar in the guideways 38. Any suitable means may be provided for shifting the actuating bar to throw the switch points. This means 70 is here shown as an operating lever 41 connected by a link 42 with a lug 43 carried by the central portion 37 of the actuating bar. The body portions of the T-shaped levers 31 are arranged at substantially right angles to 75 the cross bars of those levers, and, as stated, the cross bars 36 of the T-shaped levers and the actuating bar are both parallel with the adjacent stock rail 1 when the switch points are in their central position. Consequently 80 the pull exerted by the actuating bar 40 upon the T-shaped levers 31 is a substantially straight pull and the connections between the T-shaped levers and the switch points are such as to move the switch points simultaneously into or out of engagement with their respective rails without causing any of said switch points to bind or to come into engagement with its rail before the other switch points engage their rails. 90

Suitable locking means are provided for securing the actuating bar against movement and retaining the switch points in a fixed position. This means preferably consists of a pin 44 adapted to extend through 95 an aperture 45 in the central member 37 of the actuating bar and to engage the corresponding aperture in a support 46 beneath said bar.

The operation of the switch will be readily 100 understood from the foregoing description and its advantages will be obvious, it being apparent that the construction and arrangement of the operating mechanism is such as to effectually prevent all binding of the 105 switch points during the throwing of the same and to render the movement of the switch points free and easy.

I wish it to be understood that I do not desire to be limited to the details of construction shown and described, for obvious modifications will occur to a person skilled in the art.

Having thus fully described my invention, what I claim as new and desire to secure by 115 Letters Patent, is:—

1. In a switch of the character described, the combination, with a curved stock rail, connecting rails, and switch points, of an actuating bar having its intermediate portion 120 arranged out of alignment with the ends thereof and extending substantially parallel with said curved stock rail, and means for operatively connecting said switch points with said actuating bar. 125

2. In a switch of the character described, the combination, with a curved stock rail, connecting rails, and switch points, of an actuating bar having its intermediate portion arranged out of alignment with the ends 130

thereof and extending substantially parallel with said curved stock rail, a lever operatively connected to said actuating bar and having a cross bar arranged at substantially 5 right angles to the body portion thereof and substantially parallel with said actuating bar, and bars for operatively connecting said switch points to the cross bar of said lever.

3. In a switch of the character described, 10 the combination, with a curved stock rail, connecting rails, and switch points, of bars connecting said switch points in pairs, T-shaped levers having their cross bars connected to the respective connecting bars, and 15 an actuating bar connected to said T-shaped levers and having its intermediate portion arranged out of alinement with the ends thereof, said actuating bar and said T-shaped levers being so arranged that, when said 20 switch points are in a central position, said connecting rails, curved stock rail, actuating bar and cross bars of the T-shaped levers will extend in substantially parallel lines.

4. In a switch of the character described, 25 the combination, with a curved stock rail, connecting rails, and switch points, of bars connecting said switch points in pairs, an actuating bar having its intermediate portion arranged out of alinement with the ends 30 thereof and extending substantially parallel with said curved stock rail, means for operatively connecting said connecting bars to said actuating bar, and means for locking said actuating bar against movement.

35 5. In a switch of the character described, the combination, with a curved stock rail, connecting rails, and switch points, of bars connecting said switch points in pairs, a sectional actuating bar having its central portion arranged out of alinement with the ends 40 thereof and extending substantially parallel with said curved stock rail, means for operatively connecting said connecting bars to

said actuating bar, means for slidably supporting one of the sections of said actuating bar, and means for imparting movement to said actuating bar. 45

6. In a switch of the character described, the combination, with stock rails, two pairs 50 of curved connecting rails arranged between said stock rails, track rails, switch points for connecting the ends of one pair of said connecting rails with the respective stock rails, other switch points for connecting the ends 55 of the other pair of connecting rails with the respective track rails, and means for simultaneously actuating all of said switch points, of switch points for connecting said track rails with one pair of said connecting rails, and means for simultaneously actuating all 60 of the last-mentioned switch points.

7. In a switch of the character described, the combination, with curved stock rails, two pairs of curved connecting rails arranged 65 between said stock rails, track rails, switch points for connecting the ends of one pair of connecting rails with the respective stock rails, other switch points for connecting the ends of the other pair of connecting rails with the respective track rails, an actuating bar 70 having its intermediate portion arranged out of alinement with the ends thereof and extending substantially parallel with one of said curved stock rails, and means for connecting said actuating bar to said switch 75 points, of switch points for connecting said track rails with one pair of said connecting rails, and means for simultaneously actuating all of the last-mentioned switch points.

In testimony whereof, I affix my signature 80 in presence of two witnesses.

THOMAS W. COX.
